UNITED STATES PATENT OFFICE.

OSCAR D. KILLEBREW, OF RICHMOND, VIRGINIA.

STYLUS.

1,028,029.

Specification of Letters Patent. Patented May 28, 1912.

Application filed November 27, 1911. Serial No. 632,767.

To all whom it may concern:

Be it known that I, OSCAR D. KILLEBREW, a citizen of the United States, residing at Richmond, in the county of Henrico and 5 State of Virginia, have invented new and useful Improvements in Styli, of which the following is a specification.

The object of my invention is to provide an improved stylus adapted for use in such 10 cases where it is desired to make a large number of copies of writings by the aid of the usual carbon papers or other duplicating mediums, the stylus, according to the present invention, embodying a tip which is 15 preferably pointed toward the end and is provided with a spherical body or ball of hard material such as steel, the ball being confined by the tip to prevent displacement and it is provided with a spherical seat 20 which sustains the pressure of the ball but permits the same to revolve freely while traversing the paper in any direction, thus enabling considerable pressure to be exerted on the ball without puncturing or otherwise 25 damaging the paper or medium upon which the ball bears.

A particularly advantageous feature of 30 this invention is obtained by crimping the end of the tip to prevent displacement of the ball in one direction and introducing 35 Babbitt or other soft lubricating metal into the hollow tip above the ball to prevent upward movement thereof and to form a spherical seat to sustain the pressure of the ball, the Babbitt or soft metal acting as a 40 lubricant for the ball of steel or other hard material and thereby avoiding binding or uneven wear of the ball and insuring an even rolling action of the ball on the paper or other material.

To these and other ends, the invention consists in certain improvements and combinations and arrangements of parts, all as will be hereinafter more fully described, the 45 novel features being pointed out particularly in the claims at the end of the specification.

In the accompanying drawing:—Figure 1 is a general view of a stylus constructed in 50 accordance with the present invention; and Fig. 2 represents an enlarged axial section through the tip showing the mounting of the ball.

Similar parts are designated by the same 55 reference characters in the several views.

In the accompanying drawing, I have

shown the preferred embodiment of the invention; although it will be understood that equivalents may be substituted for certain features of the construction shown. In the 60 present instance, the stylus embodies a tip 1 which is preferably composed of sheet metal in tubular form, the lower end of the tip being tapered to approximate a point, and the upper end of the tip in this instance 65 provides a socket 2 to receive the end of a suitable handle 3.

The lower end of the tip, which is circular in cross-section, is crimped to form an 70 inturned retaining flange 5, and a ball or spherical body 6 is contained in the lower 75 end of the tip and co-operates with the retaining flange, the lower portion of the ball projecting below the retaining flange, the internal diameter of which is somewhat less than the diameter of the ball to prevent dropping of the latter from the bottom of the tip. The back or upper side of the ball 80 co-operates with a spherical seat 7 contained within the hollow tip, and this seat sustains the pressure or thrust of the ball while the stylus is in use. Preferably, the ball is composed of relatively hard material such, for example, as steel, to avoid wear thereof, and the seat is composed of relatively soft 85 material such, for example, as Babbitt or similar soft metal, as the latter will then serve as a lubricant for the ball and will thus prevent binding or uneven wear thereof. Moreover, by providing a seat of soft 90 metal, the manufacture of the stylus is greatly facilitated.

In manufacturing the stylus, it is preferable to first form the tip with the crimp or retaining flange on the lower end thereof, 95 the ball is then introduced into the upper end of the hollow tip and will center itself on the retaining flange, and finally, a small quantity of molten Babbitt or other suitable soft metal is poured into the tip while the latter is in vertical position, the ball then closing the bottom of the tip and constituting a core over which the soft metal will cast a truly spherical seat. In order to positively lock the seat from displacement under the pressure imposed thereon by the ball, that portion in which the seat is formed may be recessed or grooved internally as shown or otherwise adapted to securely anchor the seat in proper position.

I claim as my invention:—

1. A stylus comprising a tubular tip hav-

ing a tapered end formed with an inturned flange, a spherical ball coöoperative with said flange and having a portion projecting beyond said flange, and a rigid abutment 5 formed separately from the tip and inserted therein behind the ball and having a hemispherical seat revolvably engaged by the ball.

2. A stylus comprising a tubular tip having an inturned retaining flange on its lower 10 end, a spherical ball of hard material resting on said flange, and a stationary seat of relatively soft material cast in the tip above

the ball and having a hemi-spherical cavity which is revolvably engaged by the ball, the tip having means to key said seat rigidly 15 therein.

In testimony whereof I have hereunto set my hand in presence of two subscribing witnesses.

OSCAR D. KILLEBREW.
